CLAIM

The ornamental design for a doll, as shown and described.

DESCRIPTION

FIG. 1 is a perspective view of a doll showing our new design.

FIG. 2 is a side elevation view of the doll shown in FIG. 1.

FIG. 3 is a rear elevation view of the doll shown in FIG. 1.

FIG. 4 is a perspective view of the doll shown in FIG. 1 wherein a crown replaces the hat worn by the doll in FIG. 1.

FIG. 5 is a perspective view of the doll shown in FIG. 1 wherein a western style hat is shown to replace the hat worn in FIG. 1.
